WRITING INSTRUMENT

Robert E. Boyden and Richard E. Eakin, San Gabriel, Richard S. Mark, Arcadia, and Irving J. Spiro, Sherman Oaks, Calif., assignors, by mesne assignments, of one-half to Flo-Ball Pen Corporation, San Gabriel, Calif., a corporation of California, and one-half to Flo-Ball Pen Corporation, New York, N.Y., a corporation of New York

Application September 16, 1952, Serial No. 309,908

3 Claims. (Cl. 120—42.03)

This invention relates to writing instruments of the type wherein the writing tip is selectively projectable and retractable relative to the barrel so that the instrument, when not in use, may be carried in one's pocket without having to place a protecting cap over the writing tip.

The invention is particularly related to ball pens having a ball writing tip and a conduit connecting an ink reservoir to the ball. Normally, because of the viscosity of the ink and the close fit of the ball in its socket, the ink will not leak out and it is desirable to carry the pen with the ball point extending downward so as to reduce the possibility of an air lock occurring in the ink column which might otherwise occur if the pen were carried with the ball point extending upward. This situation therefore lends itself to a retractable writing unit construction wherein the pen is normally carried with the ball point downward, and pens of this nature have been disclosed and made heretofore.

Although such retractable pens are satisfactory, users from time to time forget to retract the writing unit when placing the pen in their pocket, with the result that the ball will, through continual engagement with the sides of the pocket, eventually transfer enough ink to soil one's clothing.

It therefore becomes a principal object of the present invention to automatically retract the writing tip of a writing instrument when pocketing the instrument.

Another object is to facilitate a one-hand operation of a tip projecting-retracting control of a writing instrument while holding the latter by the same hand.

Another object is to provide a retractable pen wherein the ink reservoir may be of a maximum length.

Another object is to enable one to press downwardly on the cap or push button plunger of a retractable pen while pocketing the same and without thereby projecting the writing tip.

A further object is to provide a projecting-retracting mechanism for a ball nib writing instrument which is simple and economical to manufacture and assemble, having a minimum number of parts.

The manner in which the above and other objects of the invention are accomplished will be readily understood upon reference to the following specification when read in conjunction with the accompanying drawings wherein:

Fig. 1 is a longitudinal sectional view of a retractable ball pen embodying the present invention, illustrating the ball and the writing unit in projected or writing position.

Fig. 2 is a sectional view, similar to that of Fig. 1, but illustrating the same in a pocketed condition.

Fig. 3 is a sectional view of the pen illustrating the same in retracted position.

Fig. 4 is a sectional view of the upper end of the pen illustrating the action of the pocket clip and latch when the former is pressed inwardly.

Fig. 5 is a transverse sectional view of the pen and is taken substantially along the line 5—5 of Fig. 1.

2

Fig. 6 is a side view of the spring latch and is taken in the direction of the arrow 6 in Fig. 1.

In the following specification and claims the term "fore part" and "rear" and equivalent terminology are intended to refer to the writing end and the opposite end, respectively, of the pen.

The pen comprises a barrel 10 of plastic material which tapers slightly in a forward direction and terminates in a conical barrel tip 11, preferably of metal. The tip 11 is provided with a knurled shank 12 which is press fit into the bore of the barrel 10.

The rear of the barrel is threaded onto a combined connector and bearing sleeve 13 which is provided with a knurled portion 14, the latter being press fit into a thin rear cap member 15 of metal. The wall of the latter is preferably on the order of .015 inch in thickness. A portion of the cap member 15 extends forwardly of the knurled portion 14 of the connector sleeve, and the rear part of barrel 10, when secured on the connector sleeve, fits under this latter portion.

A pocket clip 16 of resilient sheet metal material is mounted at the rear end thereof on the cap member 15. The clip is substantially U-shaped in cross-section, as shown in Fig. 5, and is preferably attached to the cap by 25 prongs, one of which is partially shown at 17, the latter extending through holes in the cap member and bent over to secure the upper end of the clip. The clip 16 extends forwardly and terminates in a bulbous tip 18 which is yieldably held against the side of the cap member by 30 virtue of the resilient nature of the clip material.

A writing unit, generally indicated at 20, is mounted to move lengthwise in the bore of the barrel. The writing unit comprises a ball writing tip 21 rotatably mounted in a pocket formed in the forward end of an ink feeding section 22 which is integral at the rear thereof with an ink reservoir 23 in the form of an elongated tube of constant diameter.

The writing unit 20 is urged rearwardly toward its retracted position shown in Fig. 3 by a helical compression spring 24 which surrounds the forward portion of the tube 23 and is seated between the lower bore of the barrel and an enlargement 25 formed on the tube 23 midway between its ends. The lower end of the bore, due to its taper, frictionally grips the lower end of the spring 24 and thus retains the same in place even when the writing unit is removed, as will be described later.

The tube 23 is slidably mounted in the sleeve 13 and abuts at its rear against a projecting-retracting device generally indicated at 26. The latter comprises a push button 27 slidably axially through an opening in the end of the cap member 15. A shank 28 of reduced diameter extends from the push button 27 through an opening in a U-shaped spring 30 and through a conical sleeve 31, the shank being peened over the sleeve to retain the parts 27, 55 30 and 31 together as an integral unit.

One of the legs 32 of the spring engages the inner surface of the cap 15 and moves along it when the writing unit is moved between its writing and retracted positions.

The other leg 33 has a portion thereof bent over at 60 right angles as seen in Fig. 5 to constitute a latching formation 34. A camming projection 35 is formed to extend through and move along an elongated slot 36 in the wall of the cap member 15. The slot 36 is located in alignment with the pocket clip 16 and the camming projection 35 is so formed that when the writing unit is in its projected writing position shown in Fig. 1 the projection 35 will engage or lie closely adjacent the inner surface of the pocket clip at a point substantially midway between its ends.

70 In the latter position, a latching shoulder 37 of the latching formation engages a second slot 45 to thereby

retain the writing unit in writing position against the action of spring 24. The slot 45 is located in line with slot 36 and under the clip 16, thus lying out of normal sight.

The writing unit may be retracted from its writing position either manually or automatically as follows: with the pen in its writing position illustrated in Fig. 1, inward pressure against the mid portion of the pocket clip 16 as illustrated in Fig. 4 will cause the clip to flex inwardly to engage the outer surface of the camming projection 35 and thus flex the spring leg 33 inwardly. This forces the latching shoulder 37 to disengage the slot 45, permitting the spring 24 to retract the writing unit and the push button device into their retracted positions shown in Figs. 3 and 4.

It will be noted, on reference to Fig. 6 that the spring leg 33 has a reduced cross-sectional area at 38, causing the foregoing flexing to occur largely in the region of this cut-out portion 38 so that the push button 27 will be retained in axial alignment by the leg 32 during such flexing of the leg 33.

In the event the user forgets to release the writing unit in the aforementioned manner when pocketing the pen and as the latter is clipped over the edge of a pocket, partly illustrated at 40 in Fig. 2, the leading edge 41 of the pocket will engage the camming projection 35. The edge 41 will then pass between the clip and the projection 35, forcing the latter to flex the leg 33 inwardly and thereby release the latching shoulder 37 so that the spring 24 can move the writing unit to its retracted position.

One of the principal features of the pen is the fact that one may press downwardly on the push button to facilitate pocketing the pen without causing the writing unit to be latched in writing condition. This is so because the latching shoulder 37 will continue to be held out of engagement with the latching slot 45 as long as the pen is clipped over the pocket edge as will be noted in Fig. 2.

In order to replace the writing unit 20 when the latter becomes exhausted of ink, the barrel 10 is unscrewed from the connector sleeve 13 and the writing unit is withdrawn from the barrel. In this condition the projecting-retracting device 26 is retained in position in the cap 15 by the frictional engagement of the spring legs or by the latching shoulder 37, should the latter be in engagement with the slot 45.

Although we have described our invention in detail in its preferred form, and have therefore used certain specific terms and language herein, it is to be understood that the present disclosure is illustrative rather than restrictive and that changes and modifications may be made thereto without departing from the spirit or scope of the claims appended hereto. For example, the cap member 15 may be formed integrally with the remainder of the barrel and of the same plastic material.

Having thus described our invention, what we desire to secure by United States Letters Patent is:

1. In a writing instrument, a hollow body having an end opening and a side wall opening, a writing point assembly reciprocably mounted within the body for projection of its point forwardly of the end opening or withdrawal rearwardly therethrough, spring means tensioning the point toward the withdrawn position, actuating means manually operable to project the point toward the forward position, a pocket clip secured to the body and extending forwardly over the side wall opening and tensioned toward the side wall, catch means within the body having a low level part and a high level part, said catch means coupled with the writing point assembly and spring tensioned to project the high level part through and beyond the side wall opening and to project the low level part into engagement with a cooperating part of the body when the writing point is moved forwardly, said body

provided with said cooperating part, said low level part when engaged with the cooperating part of the body adapted to releasably retain the writing point moved forwardly counter the tension of its spring, said high level part being disposed when projected through the side wall opening in such proximity to a part of the pocket clip that interposition of a pocket part therebetween depresses the catch sufficiently to release the low level part from engagement with the cooperating part of the body thereby releasing the writing point for withdrawal by its spring, the spring acting on such catch means being resistingly yieldable inwardly of the body upon interposition of said pocket part between said high-level part and the pocket clip, that portion of the high-level part of the spring catch projecting outwardly through the slot beyond the wall of the body being in the form of a cam sloping from the low point adjacent to the wall of the body on the side closest to the writing point end of the body to a high point more remote from the body on the side furthest from the writing end of the body.

2. In a writing instrument, a hollow body having a writing point opening at one end and having a side wall slot opening, a writing point assembly reciprocably supported within the body for projection of its point forwardly through said end opening or withdrawal of its point rearwardly within the body, spring means tensioning the point toward the withdrawn position, an actuating device coupled with the writing point assembly and projecting reciprocably through that end of the body opposite to the writing point end and manually operable to project the writing point against the tension of its spring through the writing point end opening of the body, spring catch means coupled with the actuating device to reciprocate therewith and having a high-level part and a low-level part, said spring catch means high-level part held to project through the side wall slot of the body and outwardly beyond the body wall and adapted to reciprocate within the slot upon reciprocation of the actuating device, said spring catch means low-level part held toward the side wall of the body and adapted to reciprocate within the body upon reciprocation of the actuating device, said body having an engaging part adapted to engage said low-level part when the same is moved forwardly within the body by the actuating device to project the writing point through the writing point end opening of the body, projection of the high-level part through the slot and outwardly beyond the side wall of the body permitting said low-level part to engage said engaging part, said low-level part being held inwardly of the body and disengaged from said engaging part when the high-level part of the spring catch means is disposed within the slot and does not project outwardly beyond the side wall of the body, said body having a spring pocket clip secured thereto overhanging the side wall slot, that portion of the high level part of the spring catch projecting outwardly through the slot beyond the wall of the body being in the form of a cam sloping from a low point adjacent to the wall of the body on the side closest to the writing point end of the body to a high point more remote from the body on the side furthest from the writing end of the body, said spring catch having a weaker spring than the pocket clip and being resistingly yieldable inwardly of the body upon interposition of a pocket part between said high-level part and the pocket clip withdrawing the low-level part of the spring catch from its engagement with the engaging part of the body thereby permitting retraction of the writing point assembly into the body by its spring.

3. In a writing instrument, a hollow body having an end opening and a side wall opening, a writing point assembly reciprocably mounted within the body for projection of its point forwardly of the end opening or withdrawal rearwardly therethrough, spring means tensioning the point toward the withdrawn position, actuating means manually operable to project the point toward the for-

ward position, a pocket clip secured to the body and extending forwardly over the side wall opening and tensioned toward the side wall, catch means within the body having a low level part and a high level part, said catch means coupled with the writing point assembly and spring tensioned to project the high level part through and beyond the side wall opening and to project the low level part into engagement with a cooperating part of the body when the writing point is moved forwardly, said body provided with said cooperating part, said low level part 10 when engaged with the cooperating part of the body adapted to releasably retain the writing point moved forwardly counter the tension of its spring, said high level part being disposed when projected through the side wall opening in such proximity to a part of the 15 pocket clip that interposition of a pocket part therebetween depresses the catch sufficiently to release the low level part from engagement with the cooperating part of the body thereby releasing the writing point for withdrawal by its spring, the spring acting on such catch means being resistingly yieldable inwardly of the body upon interposition of said pocket part between said high-level part and the pocket clip, that portion of the high-level part of the spring catch projecting outwardly 20 through the slot beyond the wall of the body and said 25 clip being provided with cooperating cam means, said cam means being located adjacent a portion intermediate

the length of the clip and spaced substantially from its ends and sloping from portions spaced apart to portions closely adjacent in a direction away from the writing point end of the body.
